Chas. S. St. John

Inventor:

Gifford L. Kelly

UNITED STATES PATENT OFFICE.

GIBBONS L. KELTY, OF NEW YORK, N. Y.

WINDOW-CURTAIN.

Specification of Letters Patent No. 28,585, dated June 5, 1860.

To all whom it may concern:

Be it known that I, GIBBONS L. KELTY, of the city and State of New York, have invented, made, and applied to use a certain 5 new and useful Improvement in Lambrequins or Stiff Curtains for Windows, &c.; and I do hereby declare that the following is a full and clear description of the nature and objects of my said invention, reference 10 being had to the annexed drawing, making part of this specification, wherein I have represented the stiff curtains or lambrequins to which my invention relates.

In fitting up curtains to windows it is 15 often usual to hang a stiff curtain or lambrequin across the head of the window. The same is represented at *a*, *a*, of accompanying drawing and it is attached to the lower edge of the cornice *b*; and separate curtains 20 of lace or other material may or may not be used between this fixed curtain and the window sash. These fixed or standing lambrequins or curtains are made of various shapes and extend more or less down the 25 sides of the windows. Heretofore these fixed curtains or lambrequins have been made of damask or other woven fabrics of a costly nature, and have been stiffened with a lining of buckram or other material.

30 The nature of my said invention consists in making these lambrequins or fixed curtains of buckram or similar cheap and stiff material coated with "flock" the same being a new article of manufacture possessing

both cheapness and beauty. I am enabled 35 by this invention to furnish handsome lambrequins or fixed window curtains in various designs and colors, equaling in appearance very expensive damask at a very small cost which renders the possession of ornamental 40 window curtains and head fixtures within the means of the ordinary laboring classes and operatives.

The edges of my lambrequins or fixed curtains may be ornamented with cord or 45 gimp, or with figures worked in the "flock," and for this purpose the colors may be stenciled on in any adhesive glue or gum and then coated with the "flock," said flock being ground or finely cut wool, silk 50 or other fine and handsome fibers. The whole surface of said lambrequins or fixed curtains should be covered with said flock in one or more colors, and in the desired figures or plain. 55

What I claim and desire to secure by Letters Patent as a new article of manufacture is—

The lambrequin or fixed window curtain of buckram or other material covered in 60 the manner specified.

In witness whereof I have hereunto set my signature this fourteenth day of May 1860.

GIBBONS L. KELTY.
